UNITED STATES PATENT OFFICE.

ALDRED JAMES JONES, OF NEW ORLEANS, LOUISIANA.

RAILROAD TRACK-SCALE.

1,019,478.

Specification of Letters Patent.

Patented Mar. 5, 1912.

Application filed July 11, 1911. Serial No. 637,930.

To all whom it may concern:

Be it known that I, ALDRED J. JONES, a citizen of the United States, residing at New Orleans, in the parish of Orleans and 5 State of Louisiana, have invented a new and useful Railroad Track-Scale, of which the following is a specification.

The invention relates to improvements in platform scales.

10 The object of the present invention is to improve the construction of platform scales, more especially railroad track scales, and to simplify and increase the strength and durability of the same, and to enable a single 15 pair of relatively long platform levers to sustain the entire weight of the platform or track sections and the load to be weighed, and also to provide bearing and fulcrum pivots of any desired length and strength 20 for the said levers.

A further object of the invention is to provide a railroad track scales of this character, adapted to permit an adjustment of the pivots in determining the multiplication 25 of the platform levers and in which the pivots will be permanently fixed after the multiplication of the levers has been determined, so that there can be no change of multiplication except through wear of the 30 pivot or the grinding of the edges thereof, whereby it will be impossible in weighing operations to fraudulently manipulate the scales.

Another object of the invention is to provide railroad track scales of this character in which the pivot fulcrum bearings will be suspended for permitting an oscillation or vibration of the platform or track section, so that cars may be run onto and off of the 40 same without injuring the scales or affecting the accuracy of the same.

With these and other objects in view, the invention consists in the construction and novel combination of parts hereinafter fully 45 described, illustrated in the accompanying drawings, and pointed out in the claims hereto appended; it being understood that various changes in the form, proportion, size and minor details of construction, 50 within the scope of the claims, may be resorted to without departing from the spirit

or sacrificing any of the advantages of the invention.

In the drawings:—Figure 1 is a side elevation partly in section of a railroad track scale, constructed in accordance with this invention. Fig. 2 is a plan view of the same, the platform or track section being illustrated in dotted lines. Fig. 3 is a transverse sectional view on the line 3—3 of 60 Fig. 1. Fig. 4 is a transverse sectional view on the line 4—4 of Fig. 1. Fig. 5 is an enlarged longitudinal sectional view on the line 5—5 of Fig. 2. Fig. 6 is a detail perspective view of the bearing stand. Fig. 7 is a detail perspective view of the platform bearing. Fig. 8 is a similar view of the bearing pivot holder. Fig. 9 is a detail view of another form of the suspension frame. Fig. 10 is a detail view illustrating 65 the manner of slidably interlocking the bearing stand with the corner supports. 70

Like numerals of reference designate corresponding parts in all the figures of the drawings.

In the accompanying drawings in which is illustrated the preferred embodiment of the invention, the scale is in the form of a railroad track scale, and while the improvements are designed particularly with reference to railroad track scales and similar heavy platform scales, they may be advantageously employed in the smaller class of scales, such as hay scales, and various other wagon scales and the like.

The railroad track scales comprises in its construction two longitudinal platform levers 1, designed to be made of structural steel, or other suitable material, and extending from the ends of the scales to the center thereof, that portion of the scale which sustains the weight of the platform 2 and the load being constructed in two sections, as clearly shown in Figs. 1 and 2, thereby dispensing with the numerous levers ordinarily employed in railroad track scales and the inconvenience of adjusting such levers and maintaining an accurate multiplication in the same.

Each of the platform levers 1 comprises 100 in its construction a straight longitudinal beam 3 of channel metal, or other suitable

material, and a brace 4 also constructed of channel metal, or other suitable material, and consisting of an inner diagonally arranged portion 5, and a longitudinal outer portion 6, arranged in parallelism with the outer portion of the beam 3 and connected with the latter by transverse struts or members 7 and 8, also preferably consisting of channel beams. The diagonal portion 5 extends inwardly and transversely from the longitudinal portion 6 of the brace 4 to the longitudinal beam 3, and the brace, the beam and the struts are connected together by plates and rivets in the usual manner. The platform lever 1 is provided at the inner end of the beam with a transversely disposed beam 9, secured at its inner end to the inner end of the longitudinal beams by plates and rivets, and reinforced by a brace 10 and forming a lateral extension and carrying a short terminal longitudinal portion 11. The brace 10, which is angularly disposed, is located at the opposite side of the beam 3 from the brace 4, and it extends inwardly from the outer portion of the transverse beam or extension 9 at a point intermediate of the ends of the longitudinal beam 3, and secured to the said parts by plates and rivets. The terminal longitudinal portion 11, which is constructed of channel metal similar to the transverse beam 9, is secured to the same by plates and rivets and is provided at opposite sides with point pivots 12. As platform levers of any length may be employed, they can be further braced and trussed to secure a structure of the necessary strength.

The transverse strut or member 7 of the platform levers preferably consists of an I-beam, and it is located at the outer end of the lever at the upper portion of the longitudinal beam 3 and the outer portion 6 of the brace 4, its top face being preferably arranged in flush relation with the upper faces of the said beam 3 and the outer portion 6 of the brace 4. Secured to the bottom flanges of the outer transverse strut or member 7 is a fulcrum pivot holder or support 13, constructed of suitable metal and extending across the lever, and provided at opposite sides with longitudinal flanges 14 having slots 15 for the reception of bolts 16, which pierce the bottom flanges of the outer transverse strut or member 7. The slots and bolts permit an adjustment of the fulcrum pivot holder or support to align the fulcrum pivot 17 and arrange the same in proper position. The body portion of the fulcrum pivot holder or support is approximately triangular in cross section, and it depends from the strut or member 7, the side flanges 14 being arranged at the top of the pivot holder or support, as clearly illustrated in Fig. 5 of the drawings. The cross sectional taper of the pivot holder or support reduces

the bottom portion thereof, and the said holder or support is provided in its lower face with a groove 18, extending longitudinally of the support and receiving a knife edge pivot 19, which is received within a bearing recess 20 of a bearing stand 21, extending across the space between the longitudinal beam 3 and the longitudinal portion of the brace 4, and mounted upon a transverse I-beam 22 and secured to the same by bolts 23. The bearing stand is provided at the top with upwardly projecting parallel side flanges 24, forming side walls and connected by end walls 25 to provide a lubricant receptacle for holding oil to enable the pivot and its bearing to be submerged in the lubricant, whereby the friction and wear of the parts are reduced to a minimum and the durability of the fulcrum pivot and its bearing correspondingly increased. The end walls 25 preferably consist of plates, extending across the space between the side flanges 24 and secured to the same by screws, or other suitable fastening means. The bearing stand, which is cross sectionally tapered at its lower portion, is provided at opposite sides thereof with flanges 26 for the reception of the bolts 23 to permit an adjustment and alinement of the bearing stand 21.

Secured to the lower face of the beam 22 are cross bars 27, located adjacent to the ends of the beams and projecting laterally therefrom and supported in links 28, which are suspended from corner supports by adjusting screws preferably in the form of vertical eye bolts 29. The links 28 are rounded at their ends and the lower faces of the projecting terminal portions of the cross bars 27 are correspondingly rounded at the links to fit the same. The corner supports 29 each consist of a horizontal base 30 and spaced vertical sides or standards, which are connected at their upper ends by a horizontal top bar or portion 31 through which the eye bolts pass, and upon which are arranged nuts 32, adapted to raise and lower the bearing stand for leveling the scale. The base of each of the corner supports is anchored by bolts 33, or other fastening means to a suitable foundation, and the links, which suspend the bearing stand within the corner supports, are adapted to permit a limited swing or oscillation of the stand to permit the scale to yield to the vibration and jar incident to running cars onto and off the platform, but if desired the swinging vibration of the bearing stand may be eliminated by providing grooves 34 in the inner faces of the sides or standards of the corner supports to receive the projecting ends of the cross bars 27, as illustrated in Fig. 10 of the drawings. The grooves 34, which are vertical, do not interfere with the vertical adjustment of the bearing stand for leveling the scales.

The inner transverse strut or member 8, which preferably consists of an I-beam, is located at a point intermediate of the ends of the lever adjacent to the outer end thereof, and having its lower face in flush relation with the lower faces of the longitudinal beam 3 and the outer portion 6 of the brace 4, and having a bearing pivot support or holder 35, secured to its upper face by 5 bolts 36. The bolts 36, which pierce the top flanges of the transverse strut or member 8, are arranged in slots 37 of the bottom side flanges 38 of the holder or support 35, the slots and bolts permitting an adjustment and alining of the knife edge bearing pivot 39. The pivot holder or support 35 is provided with a central longitudinal groove 40 in which the pivot 39 is mounted, and the said support or holder is provided 10 at opposite sides with vertical side flanges 41, forming side walls and connected by end walls 42, consisting of plates secured by screws, or other suitable fastening means to the side walls. The side and end walls 20 of the pivot support or holder 35 project above the plane of the pivot and form a lubricant receptacle for the reception of oil, or other suitable lubricant in which the pivot and the recess 43 of the platform 25 bearing 44 are submerged to reduce the friction and wear and increase the durability of the parts. The platform bearing 44 has a reduced lower portion in the lower face of which is the bearing recess 43, and the said 30 platform bearing is cross sectionally tapered and provided at the top with side flanges 45, having slots 46 for the reception of bolts 47, which secure the platform bearing to the transverse I-beam 48. The slots and bolts 40 permit an adjustment of the platform bearing for alining and properly positioning the same. The bearing and fulcrum pivot holders or supports, the bearing stand and the platform bearing are strongly backed 45 and reinforced by the I-beams to which they are secured, and a structure of great strength is thereby obtained. Also by the particular construction of the lever, pivots and bearings of any desired length may be 50 obtained to adapt them to the character of the scale for which they are designed and the loads to which they will be subjected. The slots and bolts of the bearing stand and the fulcrum pivot holder or support and the 55 bearing pivot holder or support and the platform bearing enable those parts to be adjusted in determining the multiplication of the levers, and after the latter has been determined and the parts secured in their 60 adjustment by the bolts or rivets, it will be impossible to tamper with the scales and manipulate the same for fraudulent weighing, as the adjustment of the bearing pivot and the fulcrum pivot are necessary to alter 65 the multiplication of the levers. Since the

point pivots are fixed with relation to the lever and the adjustment is obtained only through the fulcrum and bearing pivots, it will be impossible to change the latter without taking down the scale.

The platform 2, which is in the form of a track section, is mounted upon girders 49 of steel, or other suitable material, extending longitudinally of the platform and located beneath the same and equipped at their ends with suspension frames 50. The suspension frames 50, which are disposed transversely of the platform, are located at the end portions thereof and may consist of a horizontal top bar 51 and depending arms 52, arranged in pairs at opposite sides of the ends of the bar 51, which is secured by bolts 53, or other suitable fastening devices to the bottom flanges of the longitudinal girders 49. The horizontal top bar 51 enables a plurality of the longitudinal girders to be mounted upon it, and although only two girders are illustrated in Fig. 3 of the drawings, the number may be increased if desired. Instead, however, of employing suspension frames of 70 a length to extend entirely across the platform, spaced corner suspension frames 54, similar to that illustrated in Fig. 9 of the drawings, may be used. The corner suspension frames are designed to be arranged 75 in pairs at the ends of the platform and are provided at the top with attaching flanges 54^a, which are bolted or otherwise secured to the side girders. The said corner frames are also provided with a pair of arms arranged 80 similar to those of the suspension frame 51. The pairs of depending arms of the suspension frames are located at opposite sides of the platform bearing, and are connected at their lower ends by parallel bottom bars 55, which are suspended by links 56 and 57 from cross bars 58^a. The parallel side bars 55 are disposed transversely with relation to the platform, and they extend the entire length of the suspension frame, as clearly illustrated in Fig. 3 of the drawings. The links 56 and 57 are arranged in pairs, the lower links 56 receiving the parallel horizontal bottom bars of the suspension frame and fitted 85 in bottom bearing grooves or recesses 58 thereof. The upper links 57, which are arranged at right angles to the lower links, are linked into the same, and they are arranged upon the cross bars 58^a, which extend through the upper links. The cross bars 58^a which are horizontal, are secured by bolts 59 to the upper flanges of the beam 48 of the platform bearing, and the said cross bars 58^a project laterally from the beam and their 90 terminals extend into the space between the depending arms of the suspension frame, as clearly illustrated in Fig. 5 of the drawings. The mounting of the platform in this manner enables the same to swing both longitudinally and laterally to yield to the jars and 95 100 105 110 115 120 125 130

vibrations incident to running cars onto and off of the platform, whereby the scale may be subjected to such jars and vibrations without liability of excessively wearing or otherwise injuring the bearings or affecting the accuracy of the same.

The inner point pivots 12 are arranged in bearings 60 of loops 61, which are connected by links 63 to a rod 64, suspended from a shelf lever 65 of the ordinary construction. The shelf lever is connected by a rod 66 with a weighing beam 67, constructed and mounted in the ordinary manner, as indicated in Fig. 1 of the drawings. As the particular construction of the weighing lever and the means for connecting the same with the platform levers do not constitute a portion of the present improvement, and as any form of weighing beam and connections may be employed, further description and illustration thereof are deemed unnecessary.

Having thus fully described my invention, what I claim as new and desire to secure by Letters Patent, is:

1. A scale of the class described including a platform, a pair of platform levers located beneath the platform and extending from the outer ends thereof to the center of the scale and provided at their inner ends with fixed point pivots, fulcrum and bearing pivots secured to the outer portions of the platform levers and having a preliminary adjustment through their fastening means, which rigidly and permanently secure the said pivots to the platform levers after such preliminary adjustment, bearing stands receiving the fulcrum pivots of the levers, and bearings supporting the platform and mounted upon the bearing pivots of the levers.

2. A scale of the class described including a platform, platform levers located beneath the platform and extending from the outer ends thereof to the central portion of the scale, fulcrum pivot holders arranged at the outer ends of the levers, bearing pivot holders arranged at points intermediate of the ends of the levers, fastening means securing the said holders to the levers and permitting a preliminary adjustment of the same and rigidly securing the holders in their adjustment, fulcrum and bearing pivots carried by the said holders, bearing stands receiving the fulcrum pivots, platform bearings supporting the platform and mounted upon the bearing pivots, a weighing beam, and means for connecting the inner ends of the levers with the weighing beam.

3. A scale of the class described including a platform, levers located beneath the platform and extending from the outer ends thereof to the center of the scale and each comprising a longitudinal beam, a brace connected at an intermediate point with the longitudinal beam and having its outer portion arranged in parallelism with the

outer portion of the beam, inner and outer transverse struts connected to the outer portion of the brace and the said beam, fulcrum and bearing pivots adjustably mounted on the said struts, bearing stands 70 receiving the fulcrum pivots, and platform bearings supporting the platform and mounted upon the bearing pivots.

4. A scale of the class described including a platform, levers located beneath the platform and extending from the outer ends thereof to the center of the scale and each comprising a longitudinal beam, a brace connected at an intermediate point with the longitudinal beam and having its outer portion arranged in parallelism with the outer portion of the beam, inner and outer transverse struts connected to the outer portion of the brace and the said beam, fulcrum and bearing pivot holders provided with slots 85 or openings and having fastening means operating in the slots or openings and adjustably securing the pivot holders to the said struts, fulcrum and bearing pivots carried by the said holders, bearing stands receiving the fulcrum pivots, and platform bearings supporting the platform and mounted upon the bearing pivots.

5. A scale of the class described including a platform, levers located beneath the platform and extending from the outer ends thereof to the center of the scale, and each comprising a longitudinal beam, a brace secured to the beam at a point intermediate of the ends thereof and having an outer portion arranged in parallelism with and spaced from the outer portion of the beam, a transverse beam extending laterally from the inner end of each longitudinal beam, inner longitudinally disposed terminals carried by the transverse beams, inner and outer transverse struts connecting the brace and the longitudinal beam, fulcrum pivots secured to the outer struts, bearing pivots mounted upon the inner struts, bearing stands receiving the fulcrum pivots, and platform bearings supporting the platform and mounted upon the bearing pivots.

6. A scale of the class described including a platform, levers located beneath and extending from the outer ends of the platform to the center of the scale, and each comprising a longitudinal beam, an outer brace consisting of a diagonally arranged portion connected to the longitudinal beam, 120 and a longitudinal portion arranged in parallelism with the outer portion of the beam, a transverse beam extending laterally from the inner end of the longitudinal beam, an inner diagonal brace connecting the transverse and longitudinal beams, and inner and outer transverse struts connecting the outer brace and the outer portions of the longitudinal beam, fulcrum and bearing pivot holders secured to the outer and inner 130

struts, fulcrum and bearing pivots carried by the said holders, bearing stands receiving the fulcrum pivots, and platform bearings mounted upon the bearing pivots and supporting the platform.

7. A scale of the class described including a platform, levers located beneath the platform and fulcrumed at their outer ends, bearing pivot holders mounted upon the levers and provided with knife edge pivots and having walls surrounding the same and forming lubricant receptacles, and platform bearings supporting the platform and having portions extending into the receptacles of the supports and provided with recesses receiving the pivots.

8. In a scale of the class described, the combination with a platform, of a platform lever arranged beneath the platform and having spaced portions located at opposite sides of the scale, means for fulcruming the outer end of the lever, a bearing pivot holder extending across the space between the said portions of the lever and provided with a knife edge pivot and having side and end walls extending above the pivot to form a lubricant receptacle, and a platform bearing supporting the platform and extending across the same and having a lower portion mounted upon the said knife edge pivot and arranged within the said receptacle.

9. In a scale of the class described, the combination with a platform, of a lever located beneath the same and having spaced portions arranged at opposite sides of the scale, a transverse beam connecting the spaced portions, means for fulcruming the outer end of the lever, a bearing pivot holder mounted upon and secured to the said beam and provided with vertical walls forming a lubricant receptacle, a pivot mounted upon the said holder and extending across the scale and located within the said receptacle, and a platform bearing also extending across the scale and supporting the platform and having a reduced portion projecting into the lubricant receptacle and mounted upon the knife edge pivot.

10. In a scale of the class described, the combination with a platform, of a lever located beneath the platform and having spaced portions, means for fulcruming the outer end of the lever, a beam connecting the spaced portions, a bearing pivot holder mounted upon the said beam and extending across the lever, a knife edge pivot extending longitudinally of the said holder and secured to the same, a platform bearing also extending across the lever and mounted upon the bearing pivot, a transverse beam secured to the platform bearing, and means for connecting the platform with the last-mentioned beam.

11. In a scale of the class described, the

combination with a platform, of a lever located beneath the platform and having spaced portions, means for fulcruming the outer end of the lever, a beam connecting the spaced portions, a bearing pivot holder mounted upon the said beam and extending across the lever, a knife edge pivot extending longitudinally of the said holder and secured to the same, a platform bearing also extending across the lever and mounted upon the bearing pivot, a transverse beam secured to the platform bearing, a cross bar secured to and projecting beyond the last-mentioned beam, and links arranged upon the projecting ends of the cross bar and connecting the platform with the beam.

12. In a scale of the class described, the combination with a platform, of a lever, means for fulcruming the lever, a bearing pivot carried by the lever, a platform bearing mounted upon the pivot, a cross bar carried by the said bearing and having projecting portions, a suspension frame secured to the platform and extending below the cross bar, and links connecting the projecting portions of the cross bar with the lower portions of the suspension frame.

13. In a scale of the class described, the combination with a platform, of a lever, means for fulcruming the lever, a bearing pivot carried by the lever, a platform bearing mounted upon the pivot, a cross bar carried by the said bearing and having projecting portions, a suspension frame secured to the platform and having depending arms arranged in pairs and located at opposite sides of the projecting portions of the cross bar, and links connecting the ends of the cross bar with the arms of the suspension frame.

14. In a scale of the class described, the combination with a platform, of a lever, means for fulcruming the lever, a bearing pivot carried by the lever, a platform bearing mounted upon the pivot, a cross bar carried by the said bearing and having projecting portions, a suspension frame secured to the platform and having depending arms arranged in pairs and located at opposite sides of the projecting portions of the cross bar, horizontal bars connecting the lower ends of the arms of the suspension frame, and links receiving the said horizontal bars and arranged and depending from the projecting portions of the cross bar.

15. In a scale of the class described, the combination of a platform, a lever, means for fulcruming the lever, a bearing pivot carried by the lever, a platform bearing mounted upon the pivot, a suspension frame secured to the platform and having depending arms arranged in pairs at each side of the platform bearing, said suspension frame being also provided with horizontal bars located at opposite sides of the platform bear-

- ing and connecting the lower ends of the arms and arranged at opposite sides of the platform bearing, links also located at opposite sides of the platform bearing and receiving 5 the horizontal bars, which pass through the said links, and means carried by the bearing and extending between the said arms and receiving and supporting the links.
16. In a scale of the class described, the 10 combination with a platform, of a lever located beneath the platform and provided with spaced portions arranged at opposite sides of the platform, a transverse beam connecting the spaced portions, means for fulcrumming the lever, a bearing pivot holder secured to the said beam and extending across the space between the portions of the lever and provided with a knife edge pivot, a platform bearing also extending across the 15 lever and supported upon the said pivot, a transverse beam secured to the platform bearing and having laterally projecting means, a suspension frame secured to the platform and provided with arms arranged 20 in pairs and located at opposite sides of the said projecting means and extending below the same, and links connecting the projecting means with the lower ends of the arms.
17. In a scale of the class described, the 25 combination with a platform, of a lever having spaced portions, a fulcrum pivot extending across the lever, a bearing stand provided at the top with walls forming a lubricant receptacle and receiving the fulcrum pivot, and means for mounting the platform upon the lever.
18. In a scale of the class described, the 30 combination with a platform, of a lever having spaced portions, a pivot extending across the spaced portions, a bearing stand extending across the lever and receiving the fulcrum pivot, supports, adjusting means connecting the bearing stand with the supports for raising and lowering the stand to level 35 the scale, and means for mounting the platform upon the lever.
19. In a scale of the class described, the 35 combination with a platform, of a lever having spaced portions, a beam extending across the spaced portions, a fulcrum pivot support secured to the lower face of the beam and extending across the lever and provided at the bottom with a knife edge pivot, a bearing stand provided at the top with a bearing recess to receive the said pivot and having walls surrounding the recess and forming a lubricant receptacle, and means for mounting the platform on the lever.
20. In a scale of the class described, the 40 combination with a platform, of a lever having spaced portions, a fulcrum pivot holder extending across the space between the said portions, a pivot carried by the holder, a bearing stand receiving the pivot, a beam 45 arranged transversely of the lever and sup-
- porting the bearing stand, means connected with the beam for raising and lowering the stand, and means for mounting the platform on the lever.
21. In a scale of the class described, the 50 combination of a platform, a lever having a fulcrum pivot, a bearing stand receiving the fulcrum pivot, a beam supporting the bearing stand, supports provided with vertical adjusting screws, links connecting the 55 adjusting screws with the beam for leveling the scale, and means for mounting the platform on the lever.
22. In a scale of the class described, the 60 combination of a platform, a lever having spaced portions, a fulcrum pivot holder extending across the spaced portions and provided with a pivot, a bearing stand also extending across the said pivot, a transverse beam secured to the bottom of the stand, cross bars arranged beneath the beam and projecting therefrom, corner supports, vertical adjusting screws mounted on the corner supports, links suspended from the screws and receiving the projecting portions of the 65 said bars, and means for mounting the platform on the lever.
23. In a scale of the class described, the 70 combination with a platform, of a lever having spaced portions, a fulcrum pivot holder extending across the spaced portions, a pivot carried by the said holder, a bearing stand also extending across the said lever, a beam secured to the bearing stand at the bottom thereof, corner supports each comprising a 75 base, standards, and a top connecting the standards, vertical adjusting screws depending from the top of the corner supports, links located at opposite sides of the bearing stand and connected with the adjusting screws, means for connecting the links with the said beam, and means for mounting the platform upon the lever.
24. In a scale of the class described, the 80 combination of a platform, a lever having spaced portions, a beam connecting the spaced portions, a fulcrum pivot holder extending across the lever and fitted against the lower face of the beam and having slots 85 and provided with a pivot, a bearing stand receiving the pivot and provided at the bottom with slots, a transverse beam supporting the bearing stand, fastening devices arranged in the slots of the holder and the stand and securing the said parts to the said beams, and means for mounting the platform upon the lever.
25. In a scale of the class described, the 90 combination of a platform, a lever having spaced portions, fulcrum and bearing pivot holders extending across the space between the said portions of the lever, fulcrum and bearing pivots carried by the said holders, a bearing stand receiving the fulcrum pivot, corner supports arranged at opposite sides of 95
